UNITED STATES PATENT OFFICE.

HANS O. WESTMARK, OF AURORA, ILLINOIS, ASSIGNOR¹ OF ONE-HALF TO
ORVILLE C. MANN, OF NORA SPRINGS, IOWA.

HYDRAULIC PRESS.

SPECIFICATION forming part of Letters Patent No. 760,592, dated May 24, 1904.

Application filed October 5, 1901. Serial No. 77,700. (No model.)

To all whom it may concern:

Be it known that I, HANS O. WESTMARK, a citizen of the United States, residing at Aurora, in the county of Kane and State of Illinois, have invented certain new and useful Improvements in Hydraulic Presses, of which the following is a specification, reference being had to the accompanying drawings, forming a part thereof.

10 The purpose of this invention is to provide a hydraulic press having capacity for any determined maximum pressure, but adapted to be used for work requiring a less pressure than the maximum with a consumption of water correspondingly less than that required for the maximum work for which the press is adapted.

It consists in the features of construction set out in the claim.

20 In the drawings, Figure 1 is a vertical section through the axis of the ram of the hydraulic press embodying my invention and showing in section certain pipes and fittings not in the plane of the axial section. Fig. 2 is a section at the line 2 2 on Fig. 1. Fig. 3 is a view similar to Fig. 2, showing a modification of the arrangement of the chambers in the cylinder-head, consisting in graduating the diameters of the chambers according to a 30 different law.

A represents any convenient or desirable form of press-standard, having in the head B the cylinders or piston-chambers, which constitute a feature of my invention.

35 D is the ram. D', D², D³, D⁴, D⁵, D⁶, D⁷, D⁸, and D⁹ are pistons of different diameters operating on the ram, all parallel with each other. The main or central piston D' is attached to the 40 ram; but the remainder are free from it, only operating endwise on it. In the head B are nine piston-chambers B', B², B³, B⁴, B⁵, B⁶, B⁷, B⁸, and B⁹, corresponding to the nine pistons connected to the ram. In the drawings 45 only pistons D' D³ D⁶ are shown, pistons corresponding to the remaining characters D², D⁴, D⁵, D⁷, D⁸, and D⁹ being provided for the corresponding cylinders B², B⁴, B⁵, B⁷, B⁸, and B⁹.

B¹⁰ is a return-cylinder mounted at the upper end of the central or main cylindrical chamber B'.

D¹⁰ is a piston in the cylinder B¹⁰, and it has a stem d¹⁰ extending through the head of the chamber of the main cylinder B' and in the latter cylinder is connected to the piston D', the two pistons D' and D¹⁰ moving together in their respective chambers.

E is the main supply-pipe through which water under pressure is furnished to the cylinders for operating the ram.

F is a complete circuit-pipe encompassing the cylinder-head B, leading out from and back into the main supply-pipe E, the four-way fitting e serving to make this double junction and at the same time affording connection for the service-pipe or branch pipe leading to the main or central cylinder B'.

G is a branch pipe leading from the main supply-pipe E to the return-cylinder B¹⁰.

H is a three-way valve in the main supply-pipe between the connection therewith of the branch pipe G and the connection therewith of the circuit-pipe F.

J is a relief or waste pipe leading from the three-way valve, which is thereby adapted to be set so as to admit the water-supply to the several cylinders of the press or to take the water away from the cylinders, as required by the use of the press.

The circuit-pipe F and branch pipes F', F², F³, F⁴, F⁵, F⁶, F⁷, F⁸, and F⁹ lead to the several cylinders B', B², B³, B⁴, B⁵, B⁶, B⁷, B⁸, and B⁹, respectively. Each of these supply-pipes is provided with an independent controlling-valve K. It will be noticed that the eight cylinders grouped around the central cylinder are of four sizes only, there being two cylinders of each size, the equal cylinders of the several sizes being respectively opposite each other. This is not an essential feature of my invention, but is a desirable one for reasons which will appear.

Ordinarily in the intended mode of operation of the press the valve which controls the branch pipe F', leading to the central or main cylinder B', will not be closed, and this valve may be omitted in the construction, if so de-

sired, for in the preferred manner of use of this press the main or central cylinder B' will always be used, the force of the water which may be admitted through this cylinder corresponding to the difference in area between its piston D' and the return-piston D¹⁰, being taken as corresponding to the minimum work desired of the press, so that when only one cylinder is used it will be the central cylinder, 10 that being the one in the most advantageous position for the work obviously. All the other valves K being closed and the main controlling-valve H being open—that is, set so as to admit the water under pressure to the 15 main cylinder—that cylinder will be operated and will operate the ram, as stated, with a force determined by the difference in area between the two pistons D' and D¹⁰, for it will be noticed that the water is at all times admitted under the piston D¹⁰ into the cylinder B¹⁰ and operates opposed to the pressure which is admitted above the piston D'. To return the ram to its elevated position after the operating stroke is made, the controlling-valve will 20 be set so as to permit the water to waste, cutting off the supply, whereupon the supply-pressure operating in the return-cylinder will lift the ram to the position shown in Fig. 1. When work is to be done requiring greater 25 pressure than can be obtained from the central cylinder alone, if it is not known how much pressure is required any one or more (preferably two) opposite cylinders may be brought into operation by opening their respective controlling-valves K, other cylinders being added to the combination until the requisite pressure is obtained, and thereupon no further adjustment is required; but the stroke requiring this pressure may be repeated as 30 often as may be desired by merely operating the main controlling-valve H. In each case when the main valve is set so as to open the relief-pipe, cutting off the supply, the water-pressure operating in the return-cylinder will 35 restore the ram to elevated position, the water wasting from all the cylinders in use after release of the main controlling-valve through the relief-pipe. The advantage of arranging the cylinders in pairs whose individuals are 40 opposite each other around the central cylinder is merely that thereby the resistance of the work is equalized on both sides of the center, and side strain of the structure is avoided. However, it is not a necessity except in case 45 of severe work, because the central piston operates as a guide for the ram, and it is practicable to operate any lateral cylinder in connection with the central cylinder and without the opposite equal cylinder or any lateral cylinder alone provided its area is not exceeded by that of the return-cylinder.

I do not limit myself to making the cylinders of different capacity. Obviously a group of cylinders all of the same diameter might

be employed with great advantage in the construction shown; but by making the cylinders of different diameters a range of combinations is provided practically covering the entire field between the lowest and the greatest pressure. Thus the central or main cylinder will afford sufficient pressure for the lightest work ever required of the press or which it may be considered economical to perform with it, the smallest of the encompassing cylinders being the shortest step it is considered worth while to provide for between successive pressures. The pressure obtainable in the smallest cylinder may be termed the "unit of difference," (represented by 1.) The next larger cylinder may have an area of three, the area of 2 being provided by using the two opposite cylinders 1, having an area of one. Area 4 will be provided by using one cylinder 3 and one cylinder 1, area 5 by using one cylinder 3 and two cylinders 1, area 6 by coupling together the two opposite cylinders 3, area 7 by adding to this couple one of the cylinder 1, area 8 by using two cylinders 3 and two cylinders 1. The next size necessary to provide, therefore, would be one having an area of nine. Then area 10 would be provided by combining a nine with a one, and so on up to a total of seventeen, eighteen being provided by using two nines. The remaining steps up to and including 26 will be covered by combining with the two nines the several combinations used in producing pressure from one to eight, inclusive, the next area therefore being necessary being 27, all steps from 27 to 53, inclusive, being covered by adding one of the cylinders having area of twenty-seven to the several combinations used for the steps from 1 to 26, inclusive, all steps from 54 to 80, inclusive, being covered by adding the second cylinder having the area 27 to the several combinations used for all preceding steps. Thus any combination may be made from one to a total of eighty by steps of one by means of eight cylinders in four pairs graduated, as indicated, 1 3 9 27. If it were desired to use the cylinders only in pairs for the sake of keeping the pressure always balanced upon opposite sides of the axis, the law of gradation of the several areas would be somewhat different. The following scale will illustrate the law:

Main or central cylinder, area in excess of return-cylinder.....	10
First pair, area five each, total.....	10
First pair combined with central cylinder, total	20
Second pair, area ten each, combined with central cylinder, total.....	30
Second pair combined with central cylinder and first pair, total.....	40
Third pair, area twenty each, combined with central cylinder	50
Third pair combined with first pair and central cylinder	60

Third pair combined with second pair...	60
Third pair combined with first and second pairs and central cylinder.....	80
Fourth pair, area forty each, combined with central cylinder.....	90
Fourth pair combined with first pair and central cylinder.....	100
Fourth pair combined with second pair.....	100
Fourth pair combined with first and second pairs and central cylinder.....	120
Fourth pair combined with third pair and central cylinder.....	130
Fourth pair combined with third pair, first pair, and central cylinder.....	140
Fourth pair combined with third pair and second pair and central cylinder.....	150
Fourth pair combined with all others.....	160
The law of this gradation is obvious, and	
20 the combination may be made upon the basis of any unit of area as the effective area of the central cylinder—that is, the difference between its area and that of the return-cylinder.	
25 In Fig. 3, B^5 B^9 constitute the first pair, B^4 B^8 the second, B^3 B^6 the third, and B^2 B^7 the fourth pair, the diameters of the cylinders	

B^5 , B^4 , B^3 , and B^2 being in the proportion of 1, $\sqrt{2}$, 2 and 2, $\sqrt{2}$, as shown in said figure.

I claim—

In a hydraulic press, the combination with a ram, a multiple-chambered cylinder-head opposed to the ram; a piston attached to the ram and operating in one of the chambers of the head; a return-cylinder of less diameter mounted on the end of said main cylinder, and a piston therein extending through the main cylinder-head, connected to the piston in the latter cylinder; a plurality of additional pistons operating in the other chambers respectively against the ram; a main supply-pipe; a controlling and relief valve therein; a branch back of said valve leading to the return-cylinder, and branches forward of the valve leading to the operating-cylinders and control-valves in said latter branches respectively.

In testimony whereof I have hereunto set my hand, at Chicago, Illinois, this 18th day of September, A. D. 1901.

HANS O. WESTMARK.

In presence of—

CHAS. S. BURTON,
GEORGE H. WARNER.
